Earl W. Turner, INVENTOR.

BY
Geo. P. Kimmel.

ATTORNEY.

UNITED STATES PATENT OFFICE.

EARL W. TURNER, OF KOKOMO, INDIANA.

TIMER DISK.

Application filed March 10, 1924. Serial No. 698,220.

To all whom it may concern:

Be it known that I, EARL W. TURNER, a citizen of the United States, residing at Kokomo, in the county of Howard and State of Indiana, have invented certain new and useful Improvements in Timer Disks, of which the following is a specification.

This invention relates to a timer disk for ignition systems employed in connection with internal combustion engines, and has for its object to provide, in a manner as hereinafter set forth, a timer disk having means whereby the life thereof is materially increased, or in other words to prevent the breaking down and rapid deterioration of the insulation from which the body portion of the disk is set up.

In order that timer manufacturers can eliminate machine operations, it is necessary that they use a molded insulation material for the disk and which affords many advantages over a machine product. It is well known that the body portion or face of the disk is subjected to a very severe burning and arcing condition at the point where the contact is made and broken, that is on each side of the contact element molded into the body of the disk. When the contact is made on a timing device without a circuit breaker, there is a very noticeable flash occurring at this point and also when the contact is broken on the opposite side of the contact element there is another flash which is much more severe than at the point where contact is made and the result is the breaking down and the rapid deterioration of the material from which the body portion of the disk is molded. To overcome this breaking down and rapid deterioration of the insulation is the essential object of this invention and which is accomplished by a protective medium arranged in abutting relation with respect to the contact elements molded in the body portion of the disk.

The protection of the body portion can be accomplished in one instance by inserting a body of laminated insulation or other material on each side of a contact element at the points of make and break of the contact and with the laminated insulation molded in the body of the disk and which enables the employment of a molded disk with the advantage of laminated insulation at the particular points subject to flash.

The protection of the body or face portion can be accomplished in another manner

by setting up an annulus of laminated insulation and with the annulus provided with openings through which extend the contact elements. The walls of the openings in the annulus snugly engage the edges of the contact elements. The annulus of laminated insulation would absorb the flash and wear to which the timing disk is subjected, and further form the wearing face of the disk, or in other words, the annulus of laminated insulation would form the front face of the disk and the molded insulation the other part thereof, and by this arrangement a wearing face would be set up that would be immune from flash and burning and still the advantage retained of the molded body portion of the disk.

Further objects of the invention are to provide a timer disk, which is simple in its construction and arrangement, strong, unusually durable, thoroughly efficient in its use, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a front elevation of a timer disk in accordance with this invention.

Figure 2 is a rear elevation thereof.

Figure 3 is a section on line 3—3, Figure 1.

Figure 4 is a section on line 4—4, Figure 1.

Figure 5 is a rear elevation of a modified form.

Figure 6 is a section on line 6—6, Figure 5.

Figure 7 is a section on line 7—7, Figure 5.

Figure 8 is a section on line 8—8, Figure 5.

As before stated timer manufacturers, in the manufacture of timer disks, to eliminate machine operations employ a molded insulation material such as "bakelite" or other insulation, and which affords many advantages over a machine product, and as before

stated the molded body is subjected to a very severe burning and arcing condition at the point where contact is made and broken. To prevent this severe burning and 5 arcing condition, the body portion of the disk has connected therewith laminated insulation, as it has been found that laminated bakelite or laminated fiber is not subject to burning and arcing like the molded bakelite 10 or insulation material. However, the laminated insulation cannot be molded but must be connected to or inserted in the molded insulation from which the body portion of the disk is set up.

15 Referring to Figures 1 to 4 of the drawings, 1 denotes a disk formed of molded insulation material, such as bakelite and provided with a centrally disposed opening 2. Integral with and projecting from the disk 20 1 is a sleeve 3 of the same material from which the disk 1 is molded, and said sleeve 3 has an inwardly extending flange 4, to which is secured a metallic disk 5, formed with a threaded opening 6. The sleeve 3 and 25 disk 1 are molded together and simultaneously with the molding thereof there is embedded therein, a series of metallic contact plates 7 provided with openings 8, having threaded walls and said openings 8 register 30 with openings 9 in the disk 1. Circuit connections, not shown, are connected to the contact plates 7, at openings 9, by machine screws, and the said plates 7 are flush with the forward face of the disk 1. The foregoing construction and arrangement is well known and such foregoing construction is 35 improved to prevent the breaking down and rapid deterioration of the forward face 10 of the disk 1, and to accomplish this object, 40 at each side of a contact plate 7 is embedded in the disk 1 a protective element 11 formed of laminated bakelite or laminated fiber, or of other suitable laminated insulation material.

45 Each of the protective elements 11 is rectangular in contour and preferably of the same thickness as the thickness of a plate 7, and further each element 11 is flush with the forward face 10 of the disk 1 and with the 50 outer face of the plate 7.

With each plate 7 there is associated a pair of protective elements 11 and these latter abut against the side edges of the plate. The elements 11 are flush at their 55 ends with the ends of the plate 7.

In Figure 1 of the drawing, a carbon brush holder is indicated in dotted lines, as at 12.

60 Referring to Figures 5 to 8 of the drawings which illustrate a modified form, the timer disk is constructed of a rear section 13 of molded insulation material, such as bakelite, and a forward section 14 of laminated insulation material, such as bakelite or fiber. The sections 13 and 14 are of the same

contour and the section 13 has integral therewith the sleeve 3 of molded insulation material. Embedded in the section 13 as well as projecting forwardly therefrom are the contact plates 15 of the same construction and arrangement as the contact plates 7 and each of the plates 15 extends into an opening 16 formed in the section 14. The wall of each opening 16 snugly engage the edges of the plate 15. The section 14 surrounds the 75 plates 15 and these latter have their outer face flush with the forward face of the section 14.

The material of the molded section 13 snugly adheres to the section 14. 80

Although the plates 15 are illustrated as being embedded partly into the section 13, yet if desired, the plates 15 can be of the same thickness as the thickness of the section 14 and the material of section 13 will 85 adhere to the plate 15 and also the material of the section 14 will engage the edges of the plates to secure the latter in position.

90 Preferably the plates 7 and 15 are notched, as at 17, so that the molded material from which the disk 1 or section 13 is set up will extend into the notches and anchor the plates.

95 Preferably the disk 1 or section 13 is constructed of molded bakelite which is very serviceable from the standpoint of wear, however, it will not stand flash or burning action and by protecting the points which are subjected to flash or burning action the use of bakelite as a wearing part is retained 100 with the advantages of protection at the flashing point.

105 Bakelite is made in two forms, one is in powder which is molded into bakelite pieces by being transferred into liquid form and allowed to cure, and the other is laminated bakelite consisting of pulp and cloth combined and which is impregnated with liquid bakelite. The laminated bakelite will 110 withstand burning and flashing action which liquid bakelite molded into pieces will not stand. It is very desirable to use molded bakelite from the standpoint of economy for eliminating machine operations, and in addition pieces can be made which will conform 115 to any particular requirements, which, of course, is a great advantage, then by protecting the molded bakelite at the flash or burning points a timing disk is obtained which is unusually desirable. It is to be stated 120 however, that any other suitable character of insulation capable of being molded and any suitable character of laminated insulation can be employed in the timer disk construction.

125 What I claim is:—

1. A timer disk comprising a body formed of molded and laminated insulation material and further including contact elements, said laminated insulation material providing 130

- means to prevent burning action on the molded insulation material when said elements make and break contact.
2. A timer disk comprising a body formed of molded and laminated insulation material and further including contact elements, said laminated insulation material providing means to prevent burning action on the molded insulation material when said elements make and break contact, said laminated insulation material abutting against said elements.
3. A timer disk comprising a body of molded insulation material, spaced contact elements embedded therein, and a pair of protecting elements associated with each of said contact elements, each pair of protecting elements abutting against a contacting element and formed of laminated insulation and providing means to prevent the burning of said body of molded insulation when said contact elements make and break contact.
4. A timer disk comprising a body formed from molded insulation material, contact elements embedded in said body and flush with the forward face thereof, and protecting elements embedded in the forward face of said body and abutting against and flush with said contact elements, said protecting elements formed of laminated insulation material.
5. A timer disk comprising a body including molded and laminated insulation materials and further including contacting elements, said laminated insulation material preventing the burning of said molded insulation material when said elements make and break contact.
6. A timer disk comprising a body including molded and laminated insulation materials and further including contact elements, said laminated insulation material arranged at each side of each of said elements and constituting means to prevent the burning of the molded insulation material when said elements make and break contact. 40
7. A timer disk comprising a body of molded insulation material, a series of spaced contact elements embedded in said body and flush with the forward face thereof, and a series of protecting elements each consisting of laminated insulation material and each arranged at a side of each of said contact elements, and said protecting elements providing means to prevent the burning of said 45 molded body of insulation when the contact elements move into and out of contact. 50
8. A timer disk comprising a body of molded insulation material, a series of spaced contact elements embedded in said body and flush with the forward face thereof, and a series of protecting elements each consisting of laminated insulation material and each arranged at a side of each of said contact elements and said protecting elements 55 providing means to prevent the burning of said molded body of insulation when the contact elements move into and out of contact, each of said protecting elements being rectangular in contour and of the same 60 thickness as the thickness of a contact element. 65

In testimony whereof, I affix my signature hereto.

EARL W. TURNER.
